UNITED STATES PATENT OFFICE.

JAMES T. DOWDALL, OF GLEN MORRIS, NEW YORK.

HAT SWEATBAND.

1,420,689.

Specification of Letters Patent. Patented June 27, 1922.

Application filed November 23, 1920. Serial No. 425,944.

To all whom it may concern:

Be it known that I, JAMES T. DOWDALL, a citizen of the United States of America, residing at Glen Morris, Queens County, 5 State of New York, have invented certain new and useful Improvements in Hat Sweatbands, of which the following is a full, clear, and exact description.

This invention relates to improvements in 10 sweat bands for hats. My invention has for one of its objects to provide a sweat band for a hat that will act as a cushion to afford comfort and also to act as a gripping agent to maintain a hat on the head of the wearer; 15 in other words, to make it more difficult to blow the hat off the head. A further object of the invention is to provide a sweat band that can be preshaped and applied to a hat in assembled condition. My improved sweat 20 band is arranged so that it can be completed, entailing connecting the ends of a strip of suitable material and applying a yieldable or flexible stiffening element to cause the band to hold its shape.

25 I will now proceed to describe my invention in detail, the novel features of which I will hereinafter finally claim, reference being had to the accompanying drawing, wherein:—

30 Fig. 1 is a sectional view of a hat embodying my improvement, details of construction being omitted;

Fig. 2 is an enlarged fragmentary sectional view, illustrating one way of applying the band;

Fig. 3 is a similar view of another way of applying the band;

Fig. 4 is a detail plan view of the sweat band as it would appear when viewed in 40 the direction of the arrow in Fig. 1; and

Fig. 5 is a fragmentary detail view, illustrating one of the elements of the combination.

My improvement is made up of a strip 6 45 of suitable material secured at the ends to form a sweat band for the inside of a hat 7. In combination with the band 6 I provide a flexible element or reed, preferably a relatively thin hardened wire 8 which is located adjacent the lower edge 9 of the band. The wire or flexible reed 8 will be preferably carried by a supplemental band or strip 10 made out of material which is on the bias in order that said auxiliary band 50 or strip will yield or give longitudinally. The supplemental strip will be folded over

and the wire placed in the bight 11 thereof. When the wire is applied to the folded strip, one end will have connected therewith a tube 12, the other end being free. The wire will 60 be somewhat longer than the circumference of the strip 10, which will be approximately of the proper size for a given size hat; hence, when the free end of the wire is inserted into the open end of the tube 12, the 65 strip will be stretched or placed under tension, because in order to cause the pre-formed strip and somewhat larger wire ring (so to speak) to fit, it will be necessary to stretch the strip.

70 To produce my improved sweat band, the strip 10 will be secured by stitches 15^a, along one of its longitudinal edges, to the circular band 6. After having secured the strip 10 and band 6 together, said strip will be folded 75 over upon itself, and the reed or wire 8 placed in the bight 11 and may be secured by stitches 15. The ends of the reed or wire will not be connected until the wire has been placed in said bight or fold 11. As the 80 length of the wire will be slightly greater than the diameter of the band, it will be necessary to stretch the bias strip 10 in order to insert the free end of the wire into tube 12. One of the objects of using bias mate- 85 rial for the backing strip 10 is that it can be stretched more readily than non-bias material.

87 The article produced in the above manner will be complete in itself; that is to say, 90 will be a complete sweat band which will be preshaped and of such size as will enable it to be placed in a hat of corresponding size. To secure the band in a hat, the strip 10 will be stitched to the hat, as indicated by 16 in 95 Fig. 2. A sweat band formed in this manner provides a yieldable cushioning element for the head, the wire acting to maintain the band in such shape as to produce the cushion. The yieldable wire will always 100 accommodate itself to the shape of a head, and the backing of bias material in combination with the wire or reed permits of the provision of a sweat band element which can be preshaped and remain under tension. 105

110 Instead of securing the reed 8 directly to a band, I may secure same to an apron 17 carried by the band. (See Fig. 3.) In either case the effect will be the same.

A still further advantage of my improved sweat band is that it renders itself readily to machine sewing. As the band will be

formed, and under tension, before it is placed in a hat, it is a simple matter to stitch the reed to a hat by machine, which is a great saving over hand sewing.

5 It will be noted that the band 6 will be separated or spaced somewhat from the hat; hence, is free to stretch or act as a cushioning element. My improved construction makes it possible to maintain the band 6 spaced from the hat. It will be also noted that the wire or reed 8 is not directly secured to the band 6, but is located sufficiently approximate thereto to exert a tensioning action thereupon.

10 15 Having described my invention, what I claim is:

1. In a hat, a sweat band, a strip affixed to said band and a reed carried by the strip, the reed adapted to tension the strip outward from said band to form a cushion between the reed and band.

20 2. A sweat band consisting of a band, a strip of bias material carried by the band,

a ring carried by the strip and provided with a telescoping joint, the ring normally 25 of materially greater diameter than the band whereby when the ring is inserted in the strip the strip will be stretched by the ring to form a cushion between the band and ring.

30 3. The method of forming sweat bands for hats consisting in first securing a strip of bias material to the band and folding the biased material; in placing a yieldable reed into the bight or folded portion of the strip, 35 said reed being disconnected at its ends and of greater diameter than the diameter of the band; and in placing the bias strip under tension by causing the ends of the reed to abut.

Signed at New York city, N. Y., this 17 day of November, 1920.

JAMES T. DOWDALL.
